UNITED STATES PATENT OFFICE.

VINCENT P. TOMMINES, OF HOBOKEN, NEW JERSEY.

DESIGN FOR A SPOON.

SPECIFICATION forming part of Design No. 27,163, dated June 8, 1897.

Application filed April 24, 1897. Serial No. 633,810. Term of patent 3½ years.

To all whom it may concern:

Be it known that I, VINCENT P. TOMMINES, a citizen of the United States, residing at Hoboken, in the county of Hudson and State of 5 New Jersey, have invented and produced a new and original Design for a Spoon, of which the following is a specification, reference being had to the accompanying drawings, forming a part thereof.

Figure 1 represents the obverse of the spoon, and Fig. 2 the reverse.

The leading features of my design will appear from the following description thereof.

Within the bowl of the spoon appears the 15 representation of a monumental tomb, the lower portion of which is a square building E, having a portico F upon one side, the

whole being surmounted by a circular dome G, as shown. Upon the narrow portion of the handle appears a flag D, and beyond this 20 in the widening portion of the handle appears an eagle C, having uplifted wings, and beyond this, about the margin of the outer end of the handle, is a foliate wreath A. The reverse side of the spoon is ornamented with 25 scrollwork, as shown.

I claim—

The design for a spoon, herein shown and described.

VINCENT P. TOMMINES.
